UNITED STATES PATENT OFFICE.

IRA L. REEVES, OF SOUTH NATICK, MASSACHUSETTS.

TARGET.

1,024,651.

Specification of Letters Patent.

Patented Apr. 30, 1912.

Application filed June 20, 1911. Serial No. 634,338.

To all whom it may concern:

Be it known that I, IRA L. REEVES, a citizen of the United States, residing at South Natick, in the county of Middlesex and 5 State of Massachusetts, have invented certain new and useful Improvements in Targets, of which the following is a specification.

This invention relates to targets, and the 10 object of the invention is to provide a simple device of this character by which an accurate count can be obtained of the actual or true results of the firer.

The ordinary target consists generally of 15 a plain metallic disk having a hole at the center constituting what is known as the "bull's eye". In shooting the failure to hit the bull's eye is in a measure an error, and to mark the extent of such error, it is usual 20 to have circles or ovals concentric with the bull's eye, such circles being given a gradually decreasing value as the target increases in diameter. The said circles or ovals are formed in various ways generally 25 by grooving whereas in a paper target which is also employed the circles or ovals are printed. In scoring, the value of a hit is determined by the annular space within which it strikes. Should, however, the 30 mark of the bullet in its original diameter strike the line dividing two portions of different value, the hit of higher count is given, notwithstanding the fact that the contact of the bullet may be almost imperceptible. In paper targets the mark of a bullet can be plainly seen, but in a metal target the momentum which the bullet has 35 acquired causes the same when it strikes the face of the target to invariably flatten and 40 frequently to several times its original diameter, by virtue of which it is not possible where the bullet strikes near one of the lines to determine with accuracy what count should be given the firer, this being especially 45 the case where a bullet strikes in a lower count and the spatter of the same crosses the line separating the same from the next higher count. In this event the firer is given the higher count whereas in 50 reality his bullet may have struck in the area of smaller count.

It is the fundamental and primary purpose of my invention to eliminate such conditions as these, and this I accomplish by 55 the provision of a target of stepped form, the steps preferably extending from front to

rear of the target and being of different value. The target may be of any suitable form superficially and cross sectionally and it may have any suitable or desirable number of steps. In like manner it may be formed from any convenient material. 60

In the drawings accompanying and forming part of the present specification I have shown in detail one simple form of embodiment of the invention which to enable those skilled in the art to practice the same will be set forth fully in the following description, while the novelty of the invention will be included in the claims succeeding 65 said description. From this observation it will be evident that I do not restrict myself to such showing; I may depart therefrom in several respects within the scope of my invention included in said 70 claims.

Referring to said drawings: Figure 1 is a face view of a target involving my invention. Fig. 2 is a cross sectional view of the same. Fig. 3 is a somewhat similar view 80 but indicating diagrammatically by dotted lines courses followed by bullets under different aims, the scale of the target in said figure being somewhat exaggerated.

Like characters refer to like parts throughout the several figures. 85

As already intimated the form of the target may vary decidedly; it is shown as being circular in elevation and as having its rear concaved, although neither of these 90 points is consequential. Said target is shown having at the center a bull's eye which is usually produced by a hole therein. In addition to this the target has steps, three of which are shown and are denoted 95 respectively commencing with the innermost one by 6, 7 and 8. As already stated the number of steps is immaterial. The value to be given the bull's eye 5 and the steps or portions 6, 7 and 8 is arbitrary or may differ. It is usual to count the bull's eye 5, the portion 6 as 4, the portion 7 as 3, and the portion 8 as 2. These steps, as will be evident, extend from front to rear of the target, and their front faces are in the present case the effective areas thereof, being preferably perpendicular to the axis of the barrel of the fire arm when said barrel is held in true aiming position. The lateral portions of the said steps may be at any 100 suitable angle, although I prefer for a reason that will hereinafter appear to make 110

the lateral portions of progressively increasing pitch from front to rear of the target. That is to say, the lateral portion of the front step 6 is of the least pitch, while the 5 rear step 8 has the maximum step which construction as I stated, is preferable, although not essential, the invention residing broadly in a stepped target, no matter what the particular construction of the steps 10 thereof may be.

It will be readily understood that should a shot strike on the dividing line between the steps 6 and 7 which dividing line would be the base of the portion 6, there would be 15 no spatter of the bullet which would carry itself onto the front face of the step 6. Should the bullet, however, traverse the lateral portion of the step 6, this would leave on said step a mark which could be plainly 20 seen at ordinary gallery distances or at greater ranges by means of binoculars or their equivalents, but in this event the count would be 4. It will, therefore, be seen that I insure absolute accuracy in making counts. 25 As I have already intimated, it is conceivable that the lateral portions of the steps could be parallel with the axis of the target, but I prefer that they be at angles to said target, which as will be inferred 30 from what I have already disclosed progressively increases. The side portion of the step 6 is quite acute to said axis, and while the side portion of the step 7 is also acute to said axis, it is not so acute as the side portion 35 of the step 6, and owing to this particular relation I can secure the utmost precision. I prefer that the pitches of the side portions of the several steps coincide with the angles of flight of the bullets toward the 40 outer steps as I have indicated by dotted lines in Fig. 3. The angle of the lateral portion of the step 6, as will be seen coincides practically or substantially with that followed by the bullet or other missile toward the perpendicular surface of the step 45 7, while the angle of the lateral portion of the step 7 corresponds to the angle of the bullet in its movement toward the step 8, the angle of the side portion of the step 8 being the maximum angle of flight of a 50 bullet which would strike anywhere inside the target. Let us assume that the side portions of the steps are parallel with the axis of the target and that a bullet is ap-

proaching a point very near the base fine of 55 the base or dividing line between two steps. In this event the bullet would strike the sharp angle of the outer step and would be shaved thereby striking the next succeeding higher step. This would, therefore im- 60 properly count the firer for the higher score. By having the side portions of the steps at approximately the angles indicated, this possibility is avoided.

My target is preferably infrangible, by 65 reason of which when struck by a bullet or other missile it will not be fractured or broken; it may be formed by casting or molding either from metal or from some 70 plastic material.

What I claim is:

1. An infrangible target comprising a plurality of steps of progressively increasing size from front to rear thereof, the lateral portion of at least one front step being 75 connected with the step at the rear of it.

2. A target comprising a plurality of steps of progressively increasing size from front to rear thereof, the lateral portion of each front step being connected with the 80 step at the rear of it, and the lateral portion of the rearmost step merging into the back of the target, said lateral portions being of progressively increasing angles.

3. A target having a central hole comprising a bull's eye and also having a plurality of steps of progressively increasing size from front to rear thereof, the lateral portion of at least one step being connected 85 with the step at the rear of it. 90

4. An integral, infrangible target having a central hole constituting a bull's eye and also having a plurality of steps of progressively increasing size from front to rear thereof, the lateral portion of at least one 95 front step being connected with the step at the rear of it, the lateral portion of each front step being connected with the step at the rear of it and the lateral portion of the rearmost step merging into the back of the 100 target, said lateral portions being of progressively increasing angles.

In testimony whereof I affix my signature in presence of two witnesses.

IRA L. REEVES.
